UNITED STATES PATENT OFFICE

WELDON CHARLES ERWIN, OF YORBA LINDA, CALIFORNIA

BOTTLE ATTACHMENT

Application filed August 14, 1928. Serial No. 299,574.

This invention has to do with a bottle attachment and it is a general object of the invention to provide a device or attachment applicable to capped bottles for use in dispensing the contents therefrom.

Carbonated or charged beverages are ordinarily handled in bottles provided with metal caps known generally as crown caps. In practice the removal of the cap from a 10 bottle of carbonated fluid requires that the fluid be used in a limited length of time otherwise it becomes flat. Further, it is desirable in using carbonated fluid in the mixing of beverages to dispense it from the 15 bottle in a small stream and at a high velocity. This, of course, cannot be done with the ordinary cap unless the cap is punctured, leaving an opening which allows the contents to become flat unless used immediately. 20 An object of this invention is to provide a simple, practical and improved cap or attachment applicable to a capped bottle and operable to dispense the contents of the bottle in a small stream and to hold the bottle 25 sealed except when the device is actuated to dispense the contents.

Another object of this invention is to provide a device of the character mentioned which is extremely simple of construction 30 and manufacture and which involves a minimum number of simple parts.

A feature of the present invention is the provision of a device of the character described in which the valve or control member is normally yieldingly held in seated or closed position without the use of a spring such as is ordinarily employed in devices of this character.

Another object of the invention is to provide a simple, inexpensive and improved means for securing a device of the character mentioned on a capped bottle. The means provided by this invention is dependable, simple and convenient to operate.

A further object of the invention is to provide various improvements in the formation and arrangement of parts in a device of the character mentioned.

The various objects and features of my 50 invention will be best and more fully un-

derstood from the following detailed description of a typical form and application of the invention, throughout which description reference is had to the accompanying drawings, in which:

Fig. 1 is a view showing the device provided by this invention in the course of being applied to a capped bottle. Fig. 2 is a view showing the device in place or in operating position on a capped bottle. Fig. 3 is a detailed sectional view showing the device in position as shown in Fig. 2. Fig. 4 is a view showing the device actuated to puncture or perforate the cap of the bottle. Fig. 5 is a sectional view showing the device actuated so that the valve or control means is open. Fig. 6 is a horizontal section of line 6—6 of Fig. 2.

The device provided by this invention is intended to be used on a capped bottle such, for instance, as the standard or common form of capped bottle in which carbonated or charged beverages are sold. For purpose of example, I have disclosed a typical form of bottle having a neck 10 provided at its end with a rounded part or bead 11. The ordinary or common form of crown cap 12 is used in closing this type of bottle, the cap being provided with a crimped peripheral flange 13 to engage around the bead 11 and being provided with a washer 14 usually formed of cork. The washer is arranged in the cap to have sealing engagement between the cap and the neck of the bottle.

The device provided by my invention includes, generally, a frame or carrier 15 preferably in the form of an inverted cup adapted to fit over the cap 12 of the bottle, a body 16 mounted in the carrier to have sealing engagement with the cap 12 when the carrier is in place on the cap, means 17 for releasably attaching the carrier to the cap 12, and control or valve means 18 operable to control the passage of fluid outwardly through the body.

The carrier 15 is preferably in the form of a pressed or stamped sheet metal shell made cup shaped and adapted to be arranged over the bottle cap 12 as illustrated throughout the drawings. The carrier 15 acts pri-

100

marily as a mounting or support for the various parts of the device. In the preferred form of the invention the open end or mouth of the carrier is flared as shown at 5 to facilitate the application of the device to a cap.

The means 17 provided for securing the device in position on a cap 12 comprises a single spring member, for instance a spring wire having one end portion 30 passed through spaced openings in the carrier adjacent its open end to form a part to engage under the flange 13 of the cap 12 and having its other end portion 31 extending 10 through an elongate opening 32 in the carrier and a handle part 33 projecting from the exterior of the carrier. The part 31 of the wire can be operated in the slot or opening 32 to allow it to pass over the flange of the cap and to be sprung outwardly to be 15 disengaged from under the flange of the cap. The wire has a middle or loop portion 34 extending between the end portions 30 and 31 and around the exterior of the carrier 20 allowing free movement of the end portion 31 as above described. This particular means of securing the carrier on a cap 12 has been found to be very effective, dependable and convenient to operate.

30 In accordance with the invention, the body 16 of the device is formed of yielding elastic material, preferably rubber or other composition having the characteristics of rubber. The body 16 is mounted in the carrier and 35 has an annular face 21 adapted to seat on the top of the cap 12 in sealing engagement therewith. An opening is formed or extends upwardly in the body from its lower end forming chambers A and B separated by 40 a downwardly facing shoulder or seat 22.

The control or valve means 18 comprises, generally, a valve part 40 located at the chamber A of the body and a stem 41 extending upwardly from the valve 40 through 45 the chamber B through the top 43 of the body and through the top of the carrier 15. The valve 40 may be in the form of a disk adapted to seat upwardly against the seat 22, as clearly shown in Fig. 3 of the drawings. The stem 41 fits tightly in an opening 44 formed through the top of the body 16 and is guided in openings formed in spaced parts 45 at the top of the body 16. The stem 41 projects a substantial distance above 50 the top of the body 16 and is provided at its upper end with an operating knob 46. In accordance with my invention a flange 47 is fixed on the stem to engage or seat on the top of the body 16, the valve 40 and flange 47 being spaced apart on the stem so that 55 the body is somewhat compressed between them causing the valve 40 to be normally yieldingly held in engagement with the seat 22 through the action of the body. The yielding qualities of the body allow the stem

to be pushed downwardly to operate the valve 40 away from the seat 22, as shown in Fig. 5, in a manner to open communication between the chambers A and B.

A punch 50 projects downwardly from the valve 40 to penetrate or punch through the cap 12 when the stem is depressed or moved downwardly as shown in Fig. 4. In practice the punch 50 is made round in cross section and at its lower end 51 is bevelled off so that the cut part of the cap 12 is turned back in a manner to hold the cork washer 14 out of the opening formed by the punch.

An outlet opening 60 is provided in the body from the chamber B, and in the preferred form of the invention the opening 60 continues through a spout 61 projecting from the body. In practice the carrier 15 has a projecting part 65 forming a housing for the spout 61.

In operating the device it is applied to the cap of the bottle by first arranging the end portion 30 of the spring wire under the flange of the cap and then tilting the device over the cap from the position shown in Fig. 1 to that shown in Fig. 2 during which operation the end portion 31 of the spring wire is allowed to snap over the flange of the cap. It is to be understood, of course, that the spring wire is located in the body with reference to the seat or face 21 so that the body 16 of rubber seats tightly on the top of the cap 12 when the device is in place, as shown in Figs. 2, 3, 4 and 5 of the drawings.

To operate the device the stem 41 is moved downwardly to a position such as is shown in Fig. 4 causing the punch 50 to penetrate the cap 12, forming an opening through which the contents of the bottle can be dispensed. The stem, having been momentarily depressed to make the necessary opening in the cap, is allowed to return to its normal position as shown in Fig. 3. To dispense the contents of the bottle, the bottle is tilted so that the contents will run through the opening in the cap into the body of the device, that is into the chamber A. The stem 41 is then depressed as shown in Fig. 5 opening communication between the chambers A and B so that the contents of the bottle discharge 115 through the opening 60. When the desired amount of the contents has been dispensed, the stem 41 is released so that the resiliency of the body returns the valve 40 into engagement with the seat 22, thus sealing the chamber A from the chamber B so that pressure cannot escape from the bottle. To remove the device from the bottle it is merely necessary to operate or swing the end portion 31 of the wire outwardly to disengage it 125 from under the flange of the cap.

Having described only a typical preferred form of my invention, I do not wish to limit myself to the specific details set forth, but wish to reserve to myself any changes or 130

variations that may appear to those skilled in the art or fall within the scope of the following claims:

Having described my invention, I claim:

1. A device for use on a capped bottle including, a body to have sealing engagement with the cap of the bottle, a substantially rigid carrier encasing the body, and a member in connection with the body operable to puncture the cap and actuated by the body to normally yieldingly prevent discharge from the bottle.

2. A device for use on a capped bottle including, a body of resilient material to have sealing engagement with the cap of the bottle, a substantially rigid carrier encasing the body, and a member in connection with the body operable to puncture the cap and actuated by the body to normally yieldingly prevent discharge from the bottle.

3. A device for use on a capped bottle including, a body of resilient material to have sealing engagement with the cap of the bottle, a substantially rigid carrier encasing the body, and a member in connection with the body operable to puncture the cap and cooperating with the body to control discharge from the bottle.

4. A device for use on a capped bottle including, a body of resilient material to have sealing engagement with the cap of the bottle, a carrier for the body having means for releasable connection with the cap, and a member in connection with the body operable to puncture the cap and actuated by the resiliency of the body to control discharge from the bottle.

5. A device for use on a capped bottle including, a body of resilient material to have sealing engagement with the cap of the bottle, a carrier for the body having means for releasable connection with the cap, and a member in connection with the body operable to puncture the cap and actuated by the resiliency of the body to control discharge from the bottle, said means including a spring member carried by the carrier to engage under a part of the cap.

6. A device for use on a capped bottle including, a body of resilient material to have sealing engagement with the cap of the bottle, a carrier for the body having means for releasable connection with the cap, and a member in connection with the body operable to puncture the cap and cooperating with the body to control discharge from the bottle, said means including a single spring member carried by the carrier and having spaced parts to engage under a part of the cap.

7. A device for use on a capped bottle including, a member to engage over the cap, and means for securing said member to the cap including a spring wire carried by the

member having spaced parts to engage the cap.

8. A device for use on a capped bottle including, a member to engage over the cap, and means for securing said member to the cap including a spring wire carried by the member having spaced parts to engage the cap, one of said parts being fixed and the other movable.

In witness that I claim the foregoing I have hereunto subscribed my name this 17th day of July, 1928.

WELDON CHARLES ERWIN.
